ACCELERATION PUMP

Henry A. Eoller, Walled Lake, Mich., assignor to
 Carter Carburetor Corporation, St. Louis, Mo.,
 a corporation of Delaware

Application July 23, 1940, Serial No. 346,886

2 Claims. (Cl. 261—34)

This invention relates to fluid pumps and consists particularly in novel acceleration pump structure for carburetors.

Accelerating pump pistons actuated by resilient means often become stuck and cease to function. There is considerable time and labor expended in breaking the piston loose and removing any objectionable gum that has been allowed to accumulate by the inactivity of the pump piston.

An object of this invention is to provide a novel accelerating pump of the spring actuated type having additional spring means for providing a strong initial actuation.

Another object is to provide a spring actuated accelerating pump including means for positively actuating the pump in case it becomes stuck.

These objects and other more detailed objects hereafter appearing are attained by the structure illustrated in the accompanying drawing in which:

Fig. 1 is a vertical sectional view of an internal combustion engine carburetor taken substantially on line 1—1 in Fig. 2 with portions broken away.

Fig. 2 is a plan view of the carburetor.

Fig. 3 is a side elevation of the carburetor with portions broken away.

The carburetor illustrated comprises a down-draft mixture conduit including an air inlet horn 1, venturi 2, an outlet portion flanged at 3 for attachment to the intake manifold (not shown) of an associated engine. A choke valve 4 is pivotally mounted in the air horn and throttle valve 5 is pivoted near the outlet portion on shaft 6.

Any suitable means may be employed for operating the choke and throttle valves other than the cranks 7 and 8, respectively. Adjacent the mixture conduit is a bowl 9 within which fuel is maintained at a substantially constant level by the usual needle valve 10 actuated by the float 11.

Located within the float bowl is an accelerating pump 15 consisting of pump cylinder 16, and a piston 17 of the "air dome" type and having a spring pressed packing and an air dome 18 for receiving a portion of the fuel as the fuel in the compression chamber 19 is subjected to pressure by a downward thrust of the piston. Springs 20 and 21 are compressed or pretensioned between the piston 15 and the fuel bowl cover 22 and constantly urge the piston 15 downwardly to discharge the pump. It is to be noted that spring 21 is shorter and stronger than spring 20 and is fully extended before piston 17 reaches the end of its downward stroke. By the use of spring 21 greater initial pressure is exerted upon the piston during the first part of the opening movement of the throttle.

Fuel enters the pump chamber 19 from the fuel bowl through a screened inlet passage 23 controlled by check 24 and is discharged past the outlet check 25 through a nozzle 26 into the mixture conduit adjacent the venturis. The inlet and outlet checks communicate with pump chamber 19 through passages 27 and 28.

Pump piston 15 is connected to the throttle valve through the intermediary of piston rod 30 and lever 31, pivoted to pillow block 32 projecting above the float bowl cover and connected to crank 33 rigid with the throttle shaft by means of a link 34.

Piston rod 30 slidably received through the bowl cover 22 has one end rigidly secured to pump piston 15 while the other end is connected to the lever 31 by a link 35.

Lever 31 pivoted on the shaft 36 of pillow block 32 is adapted and arranged to actuate the usual metering rod 37 extending through the bowl cover 22. Also lever 31 is provided with a slot 38 for slidably receiving one end of link 35.

By opening the throttle very slowly the rate of downward travel of piston 15 will be controlled by the throttle. By opening the throttle rapidly the rate of downward travel of piston 15 will be controlled by the compression springs 20 and 21 as link 35 will slide in slot 38 and lever 31 will exert no downward pressure upon piston 15. If, however, piston 15 becomes stuck and the throttle valve is opened, link 35 will slide the full length of slot 38 whereupon the lever 31 will exert a positive pressure upon piston 15 to dislodge it.

It is to be noted that prestressed springs 20 and 21 exert a great initial pressure on piston 15 which gradually diminishes as the piston progresses downwardly and the limit of travel is governed by the degree of throttle opening. The throttle may be opened a predetermined distance more rapidly than the springs 20 and 21 are capable of thrusting the piston 15 downwardly a corresponding distance therefore the time consumed for discharge of fuel from the pump will be much greater than if the throttle were positively connected to the pump. Air confined in air dome 18 compressed by the downward movement of piston 15 also contributes to the continued discharge of the pump after the downward travel of piston 15 has been stopped by the lever 31.

Modifications in many respects will occur to those skilled in the art and the exclusive use of all such modifications as come within the scope of the appended claims is contemplated.

I claim:

1. In a carburetor, an induction conduit having a throttle therein, a throttle actuator, an accelerating pump having a piston, connecting means between the throttle and said piston for moving said piston to discharge position as said throttle is closed, said connecting means including a lever having a fixed pivot actuated by movement of said throttle, said lever having a guideway constructed and arranged to assume an inclined position when said throttle is substantially closed, a link member carried by said piston and engaging said guideway to form a lost motion connection between said lever and piston, said lever being shiftable on its pivot upon opening movement of said throttle to move said guideway towards a vertical position, and a spring normally moving said piston in its discharge direction as said guideway is shifted to permit movement of the pump connection.

2. In a carburetor, an induction conduit having a throttle therein, a throttle actuator, an accelerating pump having a piston, connecting means

between the throttle and said piston for moving said piston to discharge position as said throttle is closed, said connecting means including a lever having a fixed pivot actuated by movement of said throttle, said lever having a guideway constructed and arranged to assume an inclined position when said throttle is substantially closed, a link member carried by said piston and engaging said guideway to form a lost motion connection between said lever and piston, said lever being shiftable on its pivot upon opening movement of said throttle to move said guideway towards a vertical position, a spring normally moving said piston in its discharge direction as said guideway is shifted to permit movement of the pump connection, and an additional spring loosely arranged between the piston and the upper end of the cylinder initially urging said piston in its discharge direction and proportioned to be fully extended before the piston reaches the end of its downward movement.

HENRY A. BOLLER.
